UNITED STATES PATENT OFFICE.

HARRY C. WERNER, OF WHEELING, WEST VIRGINIA.

LOCK FOR SET-SCREWS.

No. 858,241.

Specification of Letters Patent.

Patented June 25, 1907.

Application filed October 5, 1906. Serial No. 337,534.

To all whom it may concern:

Be it known that I, HARRY C. WERNER, a citizen of the United States of America, and a resident of Wheeling, county of Ohio, and 5 State of West Virginia, have invented certain new and useful Improvements in Locks for Set-Screws, of which the following is a specification.

My invention relates to new and useful improvements in locks for set-screws, and more particularly to a device for locking set-screws against retraction; and it consists in the particular construction, arrangement and combination of parts which will herein- 15 after be fully described.

The object of the invention is to provide a simple, cheap and efficient device by means of which fly-wheels and the like may be secured against rotation on their shafts.

20 A further object of the invention is to provide a device for positively locking fly-wheel set-screws in impinging relation to the fly-wheel shafts, preventing the retraction of said set-screws.

25 In describing the invention in detail, reference is herein had to the accompanying drawings, forming a part of this specification, in which—

Figure 1 is a vertical section of a fly-wheel, 30 showing my invention applied thereto; Fig. 2 is a similar section of a fly-wheel hub, enlarged, more clearly illustrating the invention; and in Fig. 3 is illustrated respectively a side view, a rear edge view and a front edge 35 view of the key.

Referring to said drawings, in which like reference - numerals designate like parts throughout the several views—1 indicates a fly-wheel, 2 the shaft on which said wheel is 40 mounted, and 3 the set-screw which is screwed through the hub 4 of the wheel to impinge upon the shaft for holding said wheel in fixed relation to said shaft.

In the hub 4, at one side of the threaded 45 hole 5 through which the set-screw 3 is projected, is an inwardly inclined recess 6 which is in open communication throughout its length with said hole 5, and seated in said recess is a key 7, the lower end 8 of which is 50 substantially wedge-shaped, having its rear wall 9 inclined to substantially correspond with the inclination of the rear wall 10 of the recess 6. The front edge of the wedge-shaped end 8 of the key is beveled to a longitudinal vertical edge 11 which stands in opposing relation to the threads of the set- 55

screw 3 and which is adapted to cut into said threads upon the application of pressure to the outwardly projecting end 12 of said key. Said projecting end 12, which is substantially rectangular in cross section, stands outside the recess 6 and has its outer extremity provided with a forwardly directed beveled edge 13 which is substantially radial to said set-screw. Screwed upon said set-screw between its head 14 and the beveled end of the key 7 is a nut 15. After the set-screw has been adjusted in impinging relation to the shaft 2 and the key has been seated in the recess 6, said nut 15 is turned down 65 toward the key. When it engages the key, the lower face of the nut slides over the forwardly directed bevel 13, gradually forcing said key inward in the recess and causing the beveled edge 11 to sink into the threads of 70 the set-screw, thus preventing the retraction of said set-screw. Retraction of the nut 15 is prevented by the edge 13 of the key, which cuts into the face of the nut upon any slight rearward movement of the latter. 75

When for any reason it is desired to remove the set-screw, the edge of a chisel or like edge-tool is inserted behind the key 7 in the angle formed by the beveled edge 13 and the nut 15; then, upon striking said tool a 80 blow, said key is further sprung into the recess, disengaging the nut therefrom. When the nut has been sufficiently retracted, the key may be conveniently removed after stroking it lightly on opposite sides to loosen 85 its hold on the threads of the set-screw.

Having thus described my invention, what I claim as new, and desire to secure by Letters Patent, is—

1. In a device of the character described, 90 a set-screw mounted in the hub of a wheel in impinging relation to the shaft, a tapered key mounted in an inwardly inclined recess provided in said hub which recess is in communication throughout its length with the set-screw 100 hole, said key having a beveled edge in opposing relation to the threads of the set-screw, a nut carried by said set-screw between its head and the outwardly projecting end of said key whereby said key is forced inward in said recess, and means carried by said projecting end whereby said nut is held against retraction. 105

2. In a lock for set-screws, a set-screw projected through the hub of the wheel and having its point impinging upon the wheel shaft, a key seated in an inclined recess provided in

said hub, which recess is in open communication with the screw-hole, the rear wall of said key being inclined to correspond with the inclination of the recess, said key having a beveled edge adapted to sink into the threads of said set-screw upon the application of pressure to the outer end of the key, the outer end of the key projecting beyond said recess and having a forwardly directed bevel radial to said set-screw, and an adjustable nut carried by said set-screw in binding engagement with said radial bevel.

3. In a device of the character described, the combination with a set-screw mounted in a wheel-hub in impinging relation to its shaft, of a wedge-shaped key mounted in said hub substantially parallel to the set-screw, said

key having a beveled edge in opposing relation to the threads of the set-screw and having its outer end projected beyond the face 20 of the hub, said outer end having a bevel substantially radial to said set-screw, and a nut carried by said set-screw, said nut being adapted to be manipulated to force said key inward into thread-mutilating engagement 25 with the set-screw and to be held against retraction on said set-screw by the radially directed bevel of the key.

In testimony whereof I affix my signature in presence of two subscribing witnesses.

HARRY C. WERNER.
